UNITED STATES PATENT OFFICE.

PETER MAKRIS, OF LITCHFIELD, MINNESOTA.

DESIGN FOR A BOX.

45,999.

Specification for Design.

Patented June 23, 1914.

Application filed March 5, 1914. Serial No. 822,780. Term of patent 14 years.

To all whom it may concern:

Be it known that I, PETER MAKRIS, a citizen of the United States, residing at Litchfield, in the county of Meeker and State of Minnesota, have invented a new, original, and ornamental Design for Boxes, of which the following is a specification, reference being had to the accompanying drawings, forming part thereof.

I claim:

The ornamental design for a box, as shown.

PETER MAKRIS.
